FLOORING CONSTRUCTION

Harry S. Nagin, Pittsburgh, Pa., assignor to Reliance Steel Products Company, Rankin, Pa., a corporation of Pennsylvania

Application May 18, 1937, Serial No. 143,278

12 Claims. (Cl. 14—73)

My invention relates to flooring constructions of the type which directly support traffic without the aid of reinforcing filling or a continuous substructure and is particularly directed to the type of floors which are made from open mesh gratings formed from metal structural bars.

In certain installations of traffic-supporting roadways, such as are encountered in bridges, the floor or deck is constructed of open-work gratings or grids which are supported directly on a skeleton supporting structure such as the sills or stringers of the bridge or like structure. Such floors are, in general, constructed from sectional units, each unit being made of spaced apart bearing bars which span the space between the stringers or sills, the bearing bars, in turn, being secured together at their tops by transverse cross bars, the tops of the cross bars and the bearing bars being in the same plane. Frequently, but not always, the bearing bars are connected adjacent their bottoms by transverse tension-distributing members. The gratings present a cell-like structure to the traffic and this reticulated traffic-bearing floor is substantially skid-proof and highly wear-resistant. At the same time, it forms a comparatively light structure which permits the bridge to be economically designed and fabricated due to the lessened dead load of the floor.

Due to the large area to be floored in the average bridge, it is common practice to manufacture the gratings in unit sections or panels of convenient sizes which can be economically fabricated in the shop from commercial length bars or structural sections. These units are assembled in the bridge and joined together in various ways so as to present a substantially continuous traffic-supporting surface. The structures are usually designed so that the joints occur directly over the sills or stringers of the bridge. Because of the open construction of the floor, no dirt or foreign matter is retained on the surface, but passes through the grating entirely, except where the grating passes over the sills or stringers or other parts of the supporting framework with which the grating comes in direct contact. At these points, dirt and refuse of various kinds collect on top of the supporting sills or stringers and absorb and retain moisture so that corrosion of the bearing bars and adjacent parts of the supporting framework takes place.

One of the objects of my invention is to provide a construction which will protect the bearing bars and the sills, stringers or other parts of the supporting structure on which the bearing

bars rest so that refuse and attendant moisture cannot collect on the supporting structure and come in contact with the various surfaces and cause corrosion.

The joints between the grating units are frequently made by lapping the bearing bars of adjoining units and this necessitates that the regularity of the top cross bars be interrupted, thus tending to impair the regularity and the skid and wear-resistant properties of the traction surface, so that it is advisable that precautions be taken whereby the traction surface will not be impaired at and adjacent to the joints. The lapped bars also present a problem in corrosion as it is impossible to make a permanently water-tight joint except at considerable expense. If water gets between the overlapping bearing bars, they inevitably become rusted and the effective life of the flooring is consequently diminished. I have discovered that the joints can be protected and the traffic surface preserved by making the joint so that it will be covered by a plate set into the grating whereby the top of the floor and the top of the grating will be in the same plane. Such a plate also serves to prevent the deposition on the stringers or sills directly beneath the joint of road soil and dirt which tends to collect there and absorb and retain moisture, and thus cause rusting of the adjacent parts.

In the accompanying drawings wherein like numerals designate like parts, I have illustrated a present preferred embodiment of my invention. In the drawings:

Figure 1 is a view of a joint made according to my invention and along the line I—I of Figure 3;

Figure 2 is a cross sectional view along the line II—II of Figure 1;

Figure 3 is a top plan view of a part of the structure;

Figure 4 is a perspective view of a detail of the structure;

Figure 5 is a cross sectional view of the intersection of the floor and a part of the supporting structure;

Figure 6 is a perspective view of a detail of Figure 5;

Figure 7 is a perspective view of another form of my invention;

Figure 8 is a plan view of the same; and

Figure 9 is a perspective view of a detail.

Figures 1 through 4 show a flooring structure consisting of open top grating units or panels 2 and 3, supported on a sill or other supporting framework 4 of a bridge or like structure. Each grating consists of spaced apart bearing bars 5,

connected at their tops by cross bars 6. The bars 5 and 6 may be connected in any suitable manner, as for example, by electric pressure welding. The bearing bars 5 are connected adjacent their bottoms by traffic-distributing bars 7, although in certain designs, these bars can be omitted. The grating units are placed over the transverse supporting member 4 so that the bearing bars are transverse thereto and the ends of the bearing bars 5 of the units abut one another or lap, as desired. They are shown in Figure 3 as abutting. It is customary to weld at least some of the bearing bars to each support where they contact the support, and in some instances, the bearing bars are welded to one another so as to form a substantially continuous floor or deck.

On each side of each of the sills 4, a form plate 8 is placed so as to be in close contact with the sill 4 and to extend upwardly between the bearing bars 5 to a position substantially flush with the top of the grating. I prefer to make the form plate 8 of thin gauge metal in the shape of rectangular plates having slots 9 equal in width to the width of the bearing bars. The slots 9 are spaced apart a distance equal to the spacing apart of the bearing bars and are of a width and depth substantially equal to the width and depth of the bearing bars so that when the plate is placed in position on each side of the sill, as shown in Figure 1, a space is partitioned off above the sill, which space is filled with a suitable substantially waterproof substance 10, such as cementitious material or a plastic mass, as the case may be. Such a filling is hereinafter referred to as a filler.

In Figure 4, I have shown the form plate 8 as a rectangular sheet slightly wider than the depth of the slots. The sheet is of convenient length for handling and assembling. Again, the form plate 40 may be angularly shaped, as shown in Figure 6, which has a base portion 11 and an upright portion 12, in which upright portion the slots 13, shaped and sized similarly to the slots 9 shown in Figure 4, are located. The form plates made according to Figure 4 are placed in position in contact with the edges of the sill flanges as shown in Figure 1, and may be secured in position as by welding or friction. Form plates made according to Figure 6 are placed in position on the sill 4, as illustrated in Figure 5, in which construction, the base portion 11 extends beneath the bearing bars 5, while the upright portion extends upwardly alongside the bearing bars and provides the form against which the filler 10 is placed. It is obvious that the form plates can be made of any suitable material and of any suitable length and may extend merely between two adjacent bearing bars, if so desired. The form plates of the desired type may be secured in position by friction or in any other suitable manner, such as by spot welding. The plates may be positioned at the fabricating plant or placed in position in the field as circumstances dictate, and may be removed when the filling material has been set or may be left in position.

It is evident that the construction I have described and illustrated in both Figures 1 and 5 may be used where the sill floor comes directly under a joint, as shown in Figure 1 or where the sill is intermediate of the grating unit, as shown in Figure 5.

This construction provides complete protection for the sill and adjacent parts of the bearing bars and insures that the anti-slip qualities will not be impaired at the joints and the strength

of the flooring at the joints will not be decreased.

Figures 7 through 9 show a construction of a suitable joint for use in flooring made according to my invention. In these figures, I have shown the bearing bars 5 as overlapping one another at the joints. Each joint is placed over a suitable sill or other supporting portion of the framework 4. The ends of the bearing bars are notched from the top, as shown in Figure 9, and for a distance such that when the grating units are placed in position, the notched space 14 will accommodate a filler plate 15 which is somewhat wider than the top of sill 4. The filler plate 15 is the same in thickness as the depth of the notch 14 so that the top of the filler plate 15 is flush with the top of the adjoining gratings 2 and 3. I prefer to make the filler plate 15 with a suitable anti-skid surface which may be formed either by projections extending above the main body of the plate or depressions in the main body 20 of the plate; or again, the plate may have an abrasive top surface so as to present adequate anti-skid and traction properties. If preferred, the filler plate 15 may be of foraminous construction, in which case care should be taken 25 that the holes do not appear in the finished structure directly above the bearing bar overlapping joints. The bearing bars may be secured to one another by edge welding the end portions 16, as shown in Figure 2, or if desired, an expansion 30 joint may be provided, in which case, suitable slotted holes 17 should be provided in the ends of the bearing bars. Appropriate bolts or rods 18 may extend through the holes 17.

By the use of a form plate in the construction 35 illustrated in Figures 7 through 9, the end portions of the bearing bars are protected from direct impingement of dirt and moisture which would tend to rust the bars, especially at the joints. The filler plate also serves to prevent dust from gathering on the sill flange beneath, which dust will absorb and retain moisture and tend to corrode the bearing bars and the sills. In certain constructions, the ends of the bearing bars are prevented from tilting up and interfering with traffic.

It is customary to place the grating units or panels in a bridge or like structure in such a manner that the main bearer bars 5 run transversely of the direction of travel, in which case 50 the filler 10 and filler plate 15 run parallel to the direction of traffic and serve as a marker or strip to guide the traffic. If desired, the filler or filler plate may be colored so as to form a contrast to the surface presented by the rest of the unit 55 or panel. Whether definitely colored or not, the continuous surface overlying the supports 4 is visually quite different from the reticulated surface presented by the rest of the unit.

The filler 10 also serves a further important 60 function when galvanized or coated units are employed. It is customary to secure the bearer bars 5 to the supports 4 by welding. The finished weld presents an uncoated, metal surface and this surface, as well as adjoining surfaces the coating 65 of which has been destroyed by the welding, are readily attacked by rust. The filler 10 entirely covers these welded surfaces and effectively prevents rusting thereof.

While I have illustrated and described the preferred embodiments of my invention, it will be understood that the same is not limited thereto, but may be otherwise embodied and practiced within the scope of the following claims.

I claim:

1. In a flooring structure of the class described, an open type grating unit, a support therefor, and a filler over the support and extending from the support upwardly to the top surface of the grating unit, the rest of the unit being unfilled. 5
2. In a flooring structure of the class described, an open type grating having spaced apart parallel bearing bars resting on a support, and a substantially water-proof material filling the spaces between the bearing bars above the support from the support to the top of the bearing bars, the remainder of the said structure being open. 10
3. In a flooring construction of the class described, a grating comprising a plurality of metal strips all set on edge with their upper edge surfaces all lying in the same plane and their lower edges supported on transverse supporting members, said strips being held together at points of contact one with another with sufficient rigidity to form a unitary structure presenting a reticulated upper surface serving as a roadway, said grating being filled above the transverse supporting members only with a filler. 15
4. In a flooring construction of the class described, a grating comprising a plurality of metal strips all set on edge with their upper edge surfaces all lying in the same plane and their lower edges supported on transverse supporting members, said strips being held together at points of contact one with another with sufficient rigidity to form a unitary structure presenting a reticulated upper surface serving as a roadway, form plates extending upwardly from the sides of the transverse supporting members and between the bearing bars, and a filler in the space over the transverse supporting members and between the form plates. 20
5. In a flooring construction of the class described, a grating comprising a plurality of metal strips all set on edge with their upper edge surfaces all lying in the same plane and their lower edges supported on transverse supporting members, said strips being held together at points of contact one with another with sufficient rigidity to form a unitary structure presenting a reticulated upper surface serving as a roadway, form plates extending upwardly from the sides of the transverse supporting members and between the bearing bars, said form plates having a portion thereof in contact with the top of the transverse supporting member, and a filler in the space over the transverse supporting members and between the form plates. 25
6. A floor structure comprising a succession of grating panels, one panel interfitting with the next, the interfitting end portions of the panels being of reduced thickness to provide a transverse recess in the floor where the panels join, and a metal plate in the recess, the top of the metal plate being flush with the surface of the grating. 30
7. A floor structure comprising a succession of grating panels joining one another, said panels having bearing bars which interfit with the bearing bars of adjacent units at the joint, the interfitting end portions of the bars being of reduced thickness to provide a transverse notch in each panel where the panels join, and means in the slot to protect the interfitting ends of the bars, the top of said means being flush with the top surface of the panels. 35
8. A floor structure comprising a succession of grating panels, one panel being joined to the next, the adjoining end portions of the panels being of reduced thickness to provide a transverse recess in the floor where the panels join, a metal plate in the recess, the top of the metal plate being flush with the surface of the grating, and a transverse supporting member under the adjoining panel ends, said plate having a width at least co-extensive with the width of the support to protect the grating where it rests on the support from accumulating debris. 40
9. A floor structure comprising transverse supporting members, open gratings on the supporting members providing an open reticulated traffic-bearing floor, and means flush with the top surface of the grating over the supporting members only of a width substantially co-extensive with the width of the supporting members for excluding the accumulation of debris in the grating where the gratings rest on the supporting members, the gratings being otherwise open. 45
10. In a flooring structure of the class described, an open type grating unit, a support therefor, and means, the upper portions of which are in substantially the same plane as the top of the unit and extending longitudinally of the support and for a sufficient distance therealong to protect substantially all the contacting portions of the grating and the support. 50
11. In a flooring structure of the class described, an open type grating unit, a support therefor, and means, the upper portions of which are in substantially the same plane as the top of the unit and extending longitudinally of the support and substantially the same width as the width of the support for protecting substantially all the contacting portions of the grating and the support. 55
12. In a flooring structure of the class described, an open type grating unit, a support on which said unit rests and means for excluding accumulation of foreign matter on the support in those cells of the grating which are over the support, said means extending longitudinally of the support and having a width substantially the same as that of the support. 60

HARRY S. NAGIN.
